No. 893,588.

PATENTED JULY 14, 1908.

N. HUGHES.

GUARDED KNIFE.

APPLICATION FILED OCT. 4, 1907.

UNITED STATES PATENT OFFICE.

NELSON HUGHES, OF PORTLAND, OREGON, ASSIGNOR TO HUGHES MANUFACTURING COMPANY, OF PORTLAND, OREGON.

GUARDED KNIFE.

No. 893,588.

Specification of Letters Patent.

Patented July 14, 1908.

Application filed October 4, 1907. Serial No. 395,962.

To all whom it may concern:

Be it known that I, NELSON HUGHES, residing at Portland, county of Multnomah and State of Oregon, have invented certain 5 new and useful Improvements in Guarded Knives, of which the following is a specification.

My invention relates to certain new and useful improvements in guards or shoes for 10 rounded knives and the like and has for its object to provide a device of this character of a very simple and effective construction, which can be easily and cheaply manufactured and which will readily and effectively 15 serve its intended purposes.

In its generic nature, my invention comprises an elongated disk on one or both points of a rounded knife, a portion of which disk forms a guard or shoe for retaining the 20 knife as it passes through the leather and to enable the knife to be carried smoothly and evenly on a line, or beside the pattern without being allowed to sink into the cutting board or table, thus lessening the strength 25 required to obtain the same results and prevent the destruction of the cutting board.

With other objects in view than have been heretofore specified, the invention also comprises certain novel construction, combination and arrangement of parts, all of which 30 will be first described in detail and then be specifically pointed out in the appended claims, reference being made to the accompanying drawings, in which:—

35 Figure 1, is a perspective view of my invention as applied for use in connection with a single pointed round knife. Fig. 2, is a side elevation of a double pointed round knife showing my invention applied to both points 40 of the blade. Fig. 3, is an enlarged side elevation of the point of the knife shown in Fig. 2 with the guard attached. Fig. 4, is a section on the line 4—4 of Fig. 3. Fig. 5, is a detail view hereinafter referred to.

45 Referring now to the accompanying drawings in which like letters and numbers of reference indicate like parts in all of the figures, 1 designates the knife the blade of which may be of the form shown in Figs. 1 or 50 2, and to the point of which the guard 1^a is secured by any approved manner, such as

passing the point through the aperture in the guard and riveting or upsetting the end of the point, as indicated in Fig. 5. The guard 1^a may be forged on the blade 1^b instead of 55 riveting the same, as shown in Fig. 3, if so desired.

A designates the cutting member which may be the table upon which the leather C, or other material being cut is laid, or a suitable cutting board (not shown) may be used. 60

In the practical application of my invention, the guard 1^a is passed under the leather C, thus holding the blade 1^b as it is drawn through the leather by the operator and preventing the knife cutting into the cutting board as well as enabling the same to be guided more accurately along the line of cut than with the ordinary knife. 65

The guard disk 1^a is preferably formed of 70 elongated shape, as shown in Fig. 4, and is slightly convexed as at 3^a on either side of the plane containing the peripheral edge 2^a of the disk.

Either one, or both of the points of the 75 knife shown in Fig. 2, may be provided with the guard 1^a, as may be found convenient, thus allowing the operator to do more work with greater ease, less waste and more accuracy than with the knife without the 80 guard.

In my invention the knife 1, where it joins with the disk 1^a, is provided with doubly curved down cut edges 1^e and 2^e adjacent the guard, as shown in Fig. 3, to enable the 85 cut to be made easier and better than with the ordinary shaped knife. The doubly curved edges 1^e—2^e are known in the trade as down cutting edges, for the reason that the cutting action while the knife is being 90 drawn through the leather tends to hold the leather down on the table instead of lifting the same, as is done by an under cut knife. This will be readily apparent by reference to Figs. 1 and 3 of the drawings. 95

While the construction illustrated in the drawings and herein described shows a preferable form of my invention, it is manifest that such construction may be further modified, without departing from the spirit of 100 my invention or the scope of the appended claims.

What I claim is:—

1. A guard for rounded knives comprising a disk having a convexed top and bottom and secured to the point of a knife blade, substantially as shown and described. 20
2. The combination with a knife having a point provided with cutting edges, of a guard disk coöperatively secured to such point, substantially as shown and described. 25
- 10 3. The combination with a knife having a point provided with cutting edges, of a guard disk coöperatively secured to such point to lie with its edge in a plane at right angles to that of the cutting edge of the knife blade, substantially as shown and described. 30
- 15 4. The combination with a rounded knife, having a point, of a guard disk secured to such point to lie in a plane at right angles to

that containing the knife blade, said knife blade having double cutting edges adjacent to the guard disk, substantially as shown and described. 20

5. A two-edge blade having a pair of doubly curved edges 1°—2° combined with a guard 1^a secured to the blade adjacent to 25 said cutting edges.

6. A two-edge blade having doubly curved cutting edges 1°—2° combined with a guard 1^a secured to the blade adjacent to said cutting edges and to lie in a plane at right 30 angles to the plane of the blade.

NELSON HUGHES.
